MOKRUM COMPANY, OF CHICAGO, ILLINOIS, A CORPORATION.

TRANSMITTER FOR SELECTIVE OR PRINTING TELEGRAPHS.

1,419,677.

Specification of Letters Patent. Patented June 13, 1922.

Original application filed May 17, 1915, Serial No. 28,699. Patent No. 1,366,812, dated January 25, 1921.
Divided and this application filed January 21, 1921. Serial No. 438,809.

To all whom it may concern:

Be it known, that we, CHARLES L. KRUM and HOWARD L. KRUM, citizens of the United States, and residents of Chicago, county of Cook, and State of Illinois, have invented certain new and useful Improvements in Transmitters for Selective or Printing Telegraphs, of which the following is a full, clear, and exact description.

10 The present application is a division of an application filed by us in the United States Patent Office May 17, 1915, Serial No. 28,699, issued January 25, 1921, as Patent No. 1,366,812.

15 The invention relates to selective or printing telegraphs in which the characters or signals are represented by combinations of impulses, and in which the transmission of the signals or combinations of impulses is controlled by the formation of a tape.

20 The present invention seeks to provide means whereby the tape can be fed directly from the tape former or punching machine to the transmitter, together with means whereby any cessation of the operation of the tape former or punching machine will automatically interrupt the transmission of signals and the tape feeding means of the transmitter and whereby the renewed operation of the tape former or punching machine will automatically throw the transmitter into operation. Further objects of the invention are to provide interrupting means which will act only between completed signals, to provide an improved transmitting instrument having tape controlled means for stopping and starting the tape feeder and the transmission of signals. The invention consists in the features of improvement herein- 25

30 after set forth, illustrated in the preferred form and arrangement in the accompanying drawings and more particularly pointed out in the appended claims.

35 In the drawings, Fig. 1 is a view in elevation of the improved station instruments. Fig. 2 is an elevation of the right hand end of the instrument shown in Fig. 1. Fig. 3 is a section on the line 3—3 of Fig. 1. Fig. 4 is a horizontal section on the line 4—4 of Fig. 2. Fig. 5 is a diagrammatic view illustrating the arrangement of the tape-forming or punching mechanism and the transmitter. Fig. 6 is a view of a short section of the tape.

Any suitable mechanism for forming or punching the tape may be employed, and 55 can be actuated by a receiver mechanism under control of signals transmitted from a distant station, or, as usual, by a set of finger keys. A punching mechanism similar to that set forth in our Letters Patent of the 60 United States No. 1,182,179, dated May 9, 1916, is diagrammatically illustrated in Fig. 5. The tape A is fed through a passage or guideway formed between a plate 10 and a die-block 11. The die-block 11 is provided 65 with punches 12 for embossing, or preferably perforating the tape to form transverse rows of holes a, the perforations in the separate rows being varied so that each row represents a different character or signal. The 70 tape-forming mechanism is also provided with a punch for forming a longitudinal row of small perforations 13, which are adapted to be engaged by pin-toothed feed wheels to advance the tape. 75

A pivoted spring-held punch actuator 14 is connected by a rod 15 to the armature b of a magnet B and the punches 12 which form the transverse rows of perforations, are controlled by a set of selecting bars 16, 80 which are connected to the actuator 14 to swing therewith, but are longitudinally shiftable, so that their ends can be shifted into and out of line with the punches 12. The selecting bars 16 are actuated by a set 85 of bell cranks 17 and the latter in turn are operated by a series of upwardly projecting lugs upon a set of bails 19. Only one selecting punch and one bell crank 17 are shown, it being understood that these parts are arranged in vertical series, as set forth in the above noted patent.

90 A set of finger keys 20 (only two of which are shown) have lugs 21 for engaging and variably actuating the bails. Each key operates the outermost bail, which shifts an arm 22 carrying an insulated switch arm 23. Thus, when a key is actuated, one or more of the selecting bars 16 are shifted and a circuit is closed from a battery wire 24 100 to the switch arm 23, thence from the contact of this switch by a conductor 25 through magnet B to ground, and the magnet is energized to shift the actuator 14 and operate the punches. The actuator also advances the tape through the punch mecha- 105

nism intermittently or step-by-step by means of a spring-held pawl 25 mounted therein and arranged to engage the teeth of a ratchet 26. The ratchet is connected to a pin-toothed feed wheel 27, which engages the longitudinal row of perforations of the tape and on the backward movement of the actuator, the ratchet and feed wheel 27 are advanced one step by the pawl. A pressure roll 28 is arranged to hold the tape in snug engagement with the feed wheel 27 and the tape passes therefrom over a guide plate 29.

As the tape is formed and intermittently advanced by the punch mechanism, it is fed directly to the transmitter having a tape feeder, which, in the form shown, comprises a horizontal feed wheel 30 arranged at one end of a base plate 31. The feed wheel is arranged behind and projects through a slot 20 in an upright plate 32, so that its teeth extend into a tape guide-way formed between the plate 32 and a narrow, thin plate 33, as most clearly shown in Fig. 4. The teeth of the wheel 30 engage the longitudinal row 25 of perforations 13 of the tape and advance the same through the guide-way so that the transverse rows of perforations *a* thereof co-operate with a vertical series of selecting switches C.

30 The switches C extend through a series of eccentrics 34 on an upright shaft 35, the latter being fixed at its lower end to a small base plate 36 which is insulated from the main base plate 31. The inner, pointed ends 35 of the switches project into the tape guide-way between the plates 32 and 33 and their outer portions extend through a guiding comb bar 37 and are provided with contacts that co-operate with a series of insulated 40 contact screws 38 on an upright plate 39. A series of springs 40 tend to hold the switches in engagement with the contact screws, but as the tape engages the inner, pointed ends of the switches, each switch is held out of engagement with its contact screw unless it drops into one of the perforations of the tape. Switches C are thus variably actuated to select the combinations of impulses as the tape is advanced by the feed wheel 45. As the tape leaves the wheel 30, it is deflected forwardly by a guide plate 41.

Feed wheel 30 is mounted upon the lower end of a shaft 42 journaled in a sleeve 43 that depends from a support or head 44 swiveled upon one end of a horizontal shaft 45. A worm 46 and a worm wheel 47 are arranged within a recess in the support or head 44 and are fixed respectively to the shafts 45 and 42 to form a driving connection between shaft 45 and feed wheel 30. Sleeve 43 has a finger-piece 48 for swinging the support 44 and parts carried thereby through a short arc and move the feed wheel 30 out of the path of the tape, and this 60 oscillating movement of the support 44, is

guided by a U-shaped guide bracket 49 (see Figs. 2 and 4) that projects rearwardly from the plate 32 and engages flattened faces on the lower end of the sleeve 43. A spring 50 extends between the bracket 49 and the finger 48 and holds the parts in the normal position shown in Fig. 2, with a lug 51 on the sleeve 43 engaging an adjustable stop screw 52. An insulated arm 53, connected to the head 44 and extending downwardly 75 therefrom, engages the forked outer end of a lever 54. The inner end of this lever carries a vertical pin 55 (see Fig. 4) which, when the support 44 is shifted, engages and shifts the switches C out of the path of the 80 tape. A similar arrangement of tape feeder and tape-controlled selecting switches is set forth and claimed in Krum and Krum U. S. Letters Patent, No. 1,360,231, dated November 23, 1920.

As set forth in said patent and in the prior application, Serial No. 28,699—of which the present application is a division—the combinations of impulses selected by the tape controlled switches are imparted to 90 the line by a rotary or sun-flower switch mechanism comprising, in the present construction, the rotary switch arm *e* arranged to move over a series of contacts 1, 2, 3, 4, 5 and 6 mounted upon a disk E (see Figs 1 and 95 5); also as set forth in said patent and application, the feed wheel is preferably continuously driven when in operation during the transmission of messages to continuously advance the tape. In accordance with the present invention, means is provided for stopping and starting the transmission of signals and the feed of the tape. For this purpose and since the present instrument is adapted for use with systems which do not 100 require the transmission at regular intervals of synchronizing or correcting impulses whether or not character signals are also transmitted, the sun-flower switch arm *e* is mounted on the shaft 45, which drives the 105 tape feed wheel, and this shaft is connected to a motor by a clutch which is controlled by the operation of the tape-forming or punching mechanism.

As shown in Figs. 1 and 2, the shaft 45 115 is journaled at the outer end of cross-piece 56, which extends across a circular opening in the upper portion of a vertical bracket 57 on the base plate 31 and extends through the circular opening of a similar bracket 60. The opposite end of the shaft, as shown in dotted lines in Fig. 1, extends within a bore 120 formed within an aligned shaft 58. The latter is journaled in the upper end of a U-shaped bracket 61 (see Figs. 1 and 3). The left-hand end of the shaft 58 is provided with a gear 62 which meshes with the teeth of a pinion 63 on the shaft of a small electric motor 64, so that the shaft 58 is continuously driven during the operation of the 125 130

machine, suitable governor mechanism (not shown) being provided for maintaining the speed of the motor and the shaft 58 uniform.

Shaft 58 and shaft 45 are connected by a clutch, which, in the preferred construction shown, comprises a clutch disk 65 fixed to the end of the shaft 58, an arm 66 fixed to the adjacent end of the shaft 45 and a clutch dog 67 pivotally mounted on arm 66 and 10 pressed by a spring 68 into engagement with the clutch disk. In the form shown, the dog has a tooth 69 arranged to engage a notch 70 in the disk.

A solenoid magnet D, mounted in a U-shaped frame 71 below the clutch, has a core d connected to the lower end of a lever 72. The latter is pivoted intermediate its ends to a lug 73 on bracket 71, and its upper end is connected to a trip pin 73 which is adapted 20 to engage the clutch dog 67 and disengage it from the clutch disk 65. Trip pin 73 is mounted to slide through the upper portion of a U-shaped bracket 74 mounted on the bracket 71, and a spring 75, connected to 25 bracket 74 and to the trip, is adapted to project the latter into the path of movement of the clutch dog 67. But, when magnet D is energized, the trip pin is withdrawn and is held out of operative position, as shown in

30 Fig. 1.

The circuit of magnet D is controlled by a pair of insulated contacts 76 and 77 (see Fig. 4), contact 77 being fixed in position on the base plate and contact 76 being mounted upon the short arm 78 of a bell crank switch lever F. The latter is pivoted to the base plate at 79, and its longer arm 80 extends horizontally behind the plate 32. Arm 80 has a curved end projection forwardly in 40 front of the tape guide-way and provided with an upwardly projecting pin 81 which engages the tape (see Fig. 5) as the latter passes between the respective feeders of the tape former and the transmitter. A spring 45 82 connected to the shorter arm of the bell crank normally holds the contacts 76 and 77 in engagement to energize magnet D and hold the trip device 73 out of the path of the clutch dog 67.

50 The tape-forming or punching mechanism is, of course, operated independently of the transmitter and if it is operated with sufficient frequency and speed to maintain slack in the tape between the former and the feed-wheel 30 of the transmitter, the switch contacts 76 and 77 will remain in engagement, but if the operation of the tape-former is arrested, the continued operation of the transmitter mechanism places the 55 tape under tension and thereby shifts switch lever F to open the circuit of magnet D. Spring 75 then projects the trip pin 73, and, when the clutch dog strikes the projected pin, it is disengaged from the clutch disk 65 and the operation of switch arm e and

tape feed-wheel 30 is arrested. When the operation of the tape former is resumed, the portion of the tape between it and the transmitter becomes slack and spring 82 reengages contacts 76 and 77, energizes magnet 70 D and returns trip pin 73 to its normal position. Dog 76 then reengages the clutch disk 65 and the rotary switch arm e and the tape feeder of the transmitter are again thrown into operation. 75

Shafts 58 and 45 are driven in the direction indicated by the arrow in Fig. 3, and preferably the pivoted clutch dog 67 is rearwardly inclined with reference to the direction of movement, as shown, so that it may 80 be readily disengaged when it strikes the trip pin 73. A disk 83 having a shoulder 84 is fixed to the shaft 45 adjacent the arm 66. When clutch dog 67 is disengaged, a spring arm 85, projecting upwardly from 85 bracket 71, engages shoulder 84 and holds the shaft 45 and parts connected thereto against backward movement.

The five selecting switches C variably connect the contacts 1, 2, 3, 4 and 5 of the disk 90 E to a source of current, to thereby select the combinations of impulses which represent the different characters or signals, and which are transmitted to the line as the switch arm e passes over these contacts. In 95 the preferred form shown, the passage of the switch arm e over the contact 6 is arranged to transmit a restoring impulse. When switch F is shifted by the tape, magnet D is at once deenergized and trip pin 100 78 projected, but the clutch members are not disengaged until clutch dog 67 is moved into engagement with the trip pin. Shafts 45 and 58 and the parts connected thereto rotate in the direction indicated by the arrows 105 in Figs. 3 and 5 and clutch dog 67 is definitely positioned relatively to the transmitter switch arm e so that it cannot engage the trip pin until the switch arm occupies a position between the contacts 6 and 1. 110 Hence the trip devices are only operative at the end of the transmission of a completed character signal.

The transmitter disk E is mounted on the bracket 60 and its contacts 1 to 5 inclusive 115 are variably connected, as stated, by the selecting switches C to a source of current, but preferably a second set of five switches g operated by magnets G (see Fig. 5) are interposed between the selecting switches and 120 the contacts. Switches C are all connected to one of the branches of a conductor 24 leading from a local battery H, and these contacts are respectively connected by a set of conductors 85 to the coils of magnets G, 125 the latter being also connected to ground or to local battery by a return conductor. The switches g are connected respectively to the contacts 1, 2, 3, 4 and 5 of transmitter disk E by a set of conductors 86. The characters 130

are preferably represented by permutations of five impulses of opposite polarity, and, to this end, switches *g* form pole changers, the front and back contacts of which are connected by conductors 87 and 88 to the opposite sides of a divided battery *H'*. Conductor 87 also extends to the contact 6 of the transmitter disk *E*. As transmitter switch *e* passes over contacts 1, 2, 3, 4 and 5, permutations of positive and negative impulses varied in accordance with the operation of the tape-controlling switches *C* and representing the different character signals are imparted to the line. As switch *e* passes over contact 6, a negative restoring and printing impulse is transmitted.

The transmitter switch arm *e* is fixed to an insulated hub 99 on shaft 45 and carries a brush 100 which engages the contacts 20 of the transmitter disk *E* and is preferably provided with a piece of felt 101 for removing dust from the contacts. Hub 99 is engaged by an insulated brush 102 mounted on a block 90. The latter is pivoted on bracket 91 and is spring pressed to hold the brush against the hub.

The form of instrument shown is designed for a station, such as a news-distributing point, from which messages are transmitted to a number of receiving stations. Such an instrument preferably has means for controlling a home recorder. For this purpose, a contact disk *M* is mounted upon the upper annular portion of bracket 35 57, and a co-operating arm *m* is mounted on shaft 45. The home recording disk *M* and switch arm *m* are similar in construction and arrangement to the transmitting disk and switch arm, the disk having corresponding contacts 1, 2, 3, 4, 5 and 6 that are connected respectively by conductors 103 and 104 to the coils of a set of five magnets *N* and the coil of a magnet *P*. The conductors are also connected to the switches *n* and *p* of these magnets. Switches *n* are normally open and their contacts are connected by a conductor 105 to the contact of a normally closed unlocking switch *r*, connected to battery wire 24 and operated by a magnet *R*. The coil of magnet *R* is connected by a conductor 104' to the contact of the normally open switch *p*. Brush 102 of the transmitter switch arm is connected by a conductor 106 to the coils of a polarized relay *S* whose tongue *s* is connected to the local battery wire 24. The contact of this switch tongue is connected by a conductor 107 to the brush 108 of the recording switch arm *m*. As switches *C* are variably operated by the tape, pole changing magnets *G* are variably energized and, by means of the pole changers *g* and the conductors 86, 87 and 88, the contacts 1, 2, 3, 4 and 5 of the transmitter disk *E* are variably connected 60 either to the positive or the negative pole

of the divided battery *H'*. As the connected switch arms *e* and *m* pass over their contacts in synchronism, these positive and negative impulses pass through relay *S* and its tongue *s* is vibrated to connect and disconnect switch arm *m* to and from battery and thereby variably operate the magnets *N*.

When one of the magnets *N* is energized, the corresponding switch *n* closes a circuit from battery wire 24 through locking switch 75 *r*, conductor 105, shifted switch *n*, and the coil of the corresponding magnet *N*, so that the selected magnets remain energized until switch arm *m* passes over its contact 6. At this time, the transmitter switch arm *e* passes over its contact 6 and a negative impulse through the relay *S* connects switch arm *m* to battery and closes a circuit through the magnet *P*. This magnet quickly shifts its switch *p* to close the circuit of magnet *R*, and the latter opens the unlocking switch *r* and restores the set of magnets *N*. The latter can of course be employed for operating a suitable printer to record the transmitted messages. Brush 102 of the transmitter switch *e* may be connected, if desired, directly to the line, but it preferably extends through the coils of a polarized transmitting relay *X*, having a switch tongue *x* connected to a line conductor 131 95 and contacts are connected by conductors 130 to the positive and negative poles of a divided line battery *H''*.

Briefly stated, the operation of the preferred construction shown is as follows. 100 The tape is formed under control of finger-keys 20 and punch-actuating magnet *B*, and is advanced by the intermittently operating feed wheel 27 of the tape former. Thence the tape passes around pin 81 of switch *F* 105 and through the guide-way between the plates 32 and 33 of the transmitter. Here it is engaged by the feed wheel 30 and moves past the switches *C*. When the shafts 45 and 58 are connected by the clutch members, the transmitter switch *e* and the feed wheel 30 are continuously rotated in definite timed relation, the gearing being such that as the switch rotates through a single revolution, the tape is advanced a space equal to the 115 distance between adjacent transverse rows of perforations. As set forth in the patent and application above referred to, the set of switches *C* are preferably arranged at right angles to the path of movement of the tape 120 and the transverse rows of perforations of the tape are slightly inclined, so that the tape may be continuously advanced while permitting the accurate register of the switches *C* with the tape perforations as the 125 transmitter switch *e* passes over the corresponding contacts 1, 2, 3, 4 and 5.

As the tape passes beneath switches *C*, magnets *G* variably actuate pole changers *g* and thereby variably connect the contacts 1 130

to 5 of the transmitter disk to the opposite terminals of divided battery H', and, as the transmitter switch passes over these contacts and over contact 6, permutations of impulses 5 of opposite polarity representing the characters will be transmitted to the line by relay X, each character signal being followed by negative restoring impulse. If a home recorder is employed, the transmitted impulses 10 pass through relay S and open and close the local circuit through the home recording switch m, which, as described, variably operates a set of magnets N and a suitable printing mechanism controlled thereby. 15 Contact 76 of the tape actuating switch F is connected to the local battery and contact 77 is connected by a conductor 138 to the coil of clutch controlling magnet D. Normally, these contacts are engaged and the 20 magnet energized to hold trip pin 73 in inoperative position. If the operation of the tape former is interrupted, the tension of the tape shifts switch F, opens the circuit of magnet D and the trip pin is projected into 25 the path of clutch member 67. The latter, after the character signal then being transmitted to the line is completed, is disengaged and the operation of the transmitting switch e and tape feeder 30 and also of 30 the home-recorder, if one is employed, is arrested. As soon as the operation of the tape former relieves the tension of the tape and permits the closing of switch F to energize magnet D and withdraw trip pin 73, the 35 clutch members will again connect the shafts 45 and 58 to continue the feed of the tape and the transmission of the character signals.

Obviously, changes may be made in the 40 details set forth without departure from the essentials of the invention as defined in the claims.

We claim as our invention:

1. In selective telegraphs in which the 45 signals are represented by combinations of impulses, the combination of a set of tape-controlled impulse selectors, a switch mechanism cooperating therewith to impart the selected impulses to the line, means for feeding the tape in timed relation to the operation of 50 said switch mechanism, a tape former, and means controlled by the tape former and operable to automatically stop said switch mechanism and said tape feeding means only 55 between completed signals.

2. In selective telegraphs in which the signals are represented by combinations of impulses, the combination of a set of tape-controlled impulse selectors, a switch mechanism 60 cooperating therewith to impart the selected impulses to the line, means for feeding the tape in timed relation to the operation of said switch mechanism, a tape former, and means controlled by the tape former and operable to automatically stop and 65

start said switch mechanism and said tape feeding means only between completed signals.

3. In selective telegraphs in which the signals are of uniform length and represented by combinations of impulses, the combination of a set of tape-controlled impulse selectors, a rotary member cooperating therewith to impart the selected impulses to the line, a tape feeder operating in timed relation with said rotary member, a tape former, and means under the joint control of said tape former and feeder for automatically arresting said rotary member and said tape feeder. 80

4. In selective telegraphs in which the signals are of uniform length and represented by combinations of impulses, the combination of a set of tape-controlled impulse selectors, a rotary member cooperating therewith to impart the selected impulses to the line, a tape feeder operating in timed relation with said rotary member, a tape former, and means under the joint control of said tape former and feeder for automatically stopping and starting said rotary member and said tape feeder. 85

5. In selective telegraphs in which the signals are represented by combinations of impulses, the combination with a set of tape-controlled impulse selectors, a rotary switch mechanism cooperating therewith to impart the selected impulses to the line, means for feeding the tape in timed relation with the operation of said switch mechanism, a tape former, and means for automatically arresting and initiating the movement of said rotary switch mechanism and said tape feeding means comprising a stop-and-start clutch and a releasing trip therefor controlled by 105 said tape former and adapted to cooperate with said clutch only between completed signals. 95

6. In selective telegraphs in which the signals are represented by combinations of impulses, the combination with a set of tape-controlled impulse selectors, a rotary switch mechanism cooperating therewith to impart the selected impulses to the line, a tape feed wheel operated in timed relation with said 110 switch mechanism, a clutch and a cooperating trip operable only between completed signals to stop and start said rotary switch mechanism and said tape feed wheel, a tape former, and means controlled thereby for 115 operating said trip. 120

7. In selective telegraphs in which the signals are represented by combinations of impulses, the combination with a set of tape-controlled impulse selectors, a rotary switch 125 mechanism cooperating therewith to impart the selected impulses to the line, a tape feeder operated in timed relation with said switch mechanism, a magnet, means controlled thereby and operable only between 130

completed signals to arrest said rotary switch mechanism and said tape-feeder, a tape former, and a controlling switch for said magnet controlled by the movement of 5 the tape between said former and said feeder.

8. In selective telegraphs in which the signals are represented by combinations of impulses, the combination with a set of tape-controlled impulse selectors, a rotary switch mechanism cooperating therewith to impart the selected impulses to the line, a tape feeder operated in timed relation with said switch mechanism, a stop and start clutch for said rotary switch mechanism and said tape feeder, a controlling trip for said clutch, a tape former, and means controlled thereby for operating said trip.

9. In selective telegraphs in which the signals are represented by combinations of impulses, the combination with a set of tape-controlled impulse selectors, a rotary switch

mechanism cooperating therewith to impart the selected impulses to the line, a tape feeder operated in timed relation with said switch mechanism, a stop and start clutch for said rotary switch mechanism and said tape feeder, a controlling trip for said clutch, a tape former, and an electro-magnet controlled thereby for operating said trip. 25 30

10. In selective telegraphs, a transmitter comprising a set of tape-controlled impulse selectors, a rotary switch mechanism for imparting the selected impulses to the line, a feed-wheel for the tape, a common drive 35 shaft for operating said switch mechanism and said feed wheel in timed relation, a stop-and-start clutch for said shaft, a trip effective only between completed signals for controlling said clutch, a tape former, and means 40 under the joint control of said tape former and said feed wheel for operating said trip.
